AUTOMATIC JUMP ROPE

Byron L. Wolfson, Hollywood, Calif.

Application May 21, 1958, Serial No. 736,746

8 Claims. (Cl. 185—37)

The present invention relates generally to mechanisms for rotating elongated flexible material and more particularly to an apparatus for rotating one end of a jump rope, the other end of which is secured to a suitable support.

Briefly describing the general concept of the invention, an elongated shaft is rotatably supported in a generally horizontal position by two bearing structures attached to a stationary frame. Disposed on one end of the shaft, externally of the frame, is a weighted arm which is generally perpendicular to the shaft. A rope is adapted to be attached to the end of this arm and a source of motor power is secured to the shaft to produce rotation thereof. The weighted arm is employed to reduce the angular velocity of the arm on its upward movement, thereby to simulate the movement of a jump rope when it is propelled by human means.

The apparatus for rotating the shaft may take several forms and in one specific embodiment of the invention comprises two spiral springs disposed about the shaft and each having one end secured to the shaft and the other end secured to the frame. The convolutions of the springs are oppositely directed so that when one spring is wound, the other one is unwound. A crank handle is disposed on an end of the shaft, opposite to the end to which the arm is attached, and initially the crank is operated so that one of the spiral springs is wound and the other is unwound. Upon releasing the handle, the shaft rotates in one direction, for example for twenty turns, and then rotates back in the opposite direction for approximately nineteen turns. The oscillatory movement of the shaft therefore conforms to that of a damped oscillatory body and the mechanism may continue to oscillate back and forth for a considerable length of time, for example, fifteen to twenty minutes.

Such an apparatus may be employed by a child who wishes to jump rope and does not have a playmate available for rotating the rope. The rope has one end attached to a suitable stationary object and the other end attached to the end of the weighted arm and the mechanism of the invention is displaced by a suitable distance from the stationary member so as to provide a loop which just barely drags the ground. The apparatus is then cranked and released, providing a continuing motion. Smaller children may not wish to have a rope which is continually rotating in the same direction, but may wish merely to have a rope which oscillates to say 180° at a relatively slow pace, so that a child may jump each time the rope passes in either direction under the child. The apparatus of the present invention may be readily modified, to provide either effect, by either of two arrangements. In a first arrangement a straight leaf spring is secured to the shaft and suitable stops are secured to the frame to intercept the free end of the leaf spring at spaced points about its path of rotation. The apparatus may be initially cranked so that the end of the leaf spring engages one of the stops and is tensioned thereby, and then the apparatus is released. By suitably choosing the

2

natural period of oscillation of the weighted arm and of the spring, the oscillations of the arm may be sustained for a considerable period of time. In a modification of this latter embodiment of the invention, two oppositely directed spiral springs may be employed in conjunction with the leaf spring in order to provide a sustained spring force on the shaft in the interval between movement of the free end of the leaf spring between the stops.

It is, accordingly, a broad object of the present invention to provide a mechanism for rotating a jump rope which will simulate the motion of a jump rope when propelled by human means.

It is another object of the present invention to provide a mechanism for rotating a jump rope which produces sustained oscillation of the rope over a relatively long period of time.

It is yet another object of the present invention to provide a mechanism for rotating a jump rope which is spring actuated and which may rotate the rope first in one direction and then in another direction for a sustained period of time.

The above and still further objects, features and advantages of the present invention will become apparent upon consideration of the following detailed description of two specific embodiments thereof, especially when taken in conjunction with the accompanying drawings, wherein:

Figure 1 is a perspective view of one embodiment of the present invention;

Figure 2 is a cross-sectional view of a side elevation of the first embodiment of the apparatus of the present invention;

Figure 3 is a detailed view of the spring motor of the first embodiment of the apparatus of the invention;

Figure 4 is a detailed view of the method of connecting the motor springs to the frame of the first embodiment of the invention;

Figure 5 is a second detailed view of the spring motor of the first embodiment of the invention;

Figure 6 is a detailed view of the spring motor of a second embodiment of the invention;

Figures 7 and 8 are modifications of the stand structure of the apparatus of the present invention;

Figure 9 is an illustration of a modification of the leg structure of the present invention; and

Figure 10 is a top view of Figure 6.

Referring specifically to Figure 1 of the accompanying drawings, there is provided a frame, generally designated by the reference numeral 1, comprising a first hollow, inverted U-shape member 2 and a second hollow, inverted U-shape member 3, spaced from and disposed parallel to the first. The U-shape frames 2 and 3 are interconnected by a bar 4 which is secured to and disposed perpendicularly of the frame members 2 and 3. Disposed within each of the hollow legs of the U-shape member 2 is a tubular leg 6 which is vertically adjustable with respect to the member 2 and which may be secured in any given vertical position by means of thumb screw 7. Similarly, the frame 3 is provided with two legs 8 which may slide internally of the hollow side legs of the U-shape frame 3 and are secured in a given position by means of thumb screw 9.

As a result of the utilization of the hollow inverted U-shape frames 2 and 3 and the adjustable legs 6 and 8, the height of the frame with respect to the ground may be readily adjusted in order to conform to the height of the child who is employing the structure.

Disposed between the legs of the U-shape member 2 is a hub 11 which is supported between the legs of the member 2 by means of a plurality of radially extending spokes 12. Similarly, a hub 13 is disposed between the

legs of the U-shape frame 3 and supported therebetween by a plurality of radially extending spokes or bars 14. The hubs 11 and 13 are axially aligned and are adapted to support a crank shaft 16 of a crank generally designated by the reference numeral 17 and having a crank handle 18. The crank handle 18 is disposed outwardly of the frame member 3, while the crank shaft 16 extends through the hub 11 and forwardly of the frame member 2. An adjustable collar 19 is disposed about the crank shaft 16 and is normally maintained in engagement with the hub 17 so as to prevent end motion of the crank shaft 16.

Rigidly secured to the shaft 16 adjacent the hub 11 is a wheel 21 which serves as a partial guide for two spiral springs 22 and 23. The spiral springs 22 and 23 are disposed about the shaft 16, and have one end 24 of the spring 23 as viewed in Figure 3 secured to the shaft 16. The other end of the spring 23, which is designated by the reference numeral 26, is secured to a U-shaped retainer 27 disposed on the shaft 4 while the corresponding end of the spiral spring 22 is secured to a U-shaped member 28 disposed on a surface of the bar 4. The ends of the spring are formed generally into loops 29 so that they curve about the U-shaped retaining members and are thereby secured thereto. The springs 22 and 23 are disposed on opposite sides of the wheel 21 in close proximity thereto so that their adjacent edges are guided by the wheel. If necessary, wheels or cross members may be disposed on the other sides of the springs 22 and 23 to provide further guide means therefor. The convolutions of the springs 22 and 23 are oppositely directed, so that when one of the springs is wound the other spring is unwound. Winding of one of the springs and unwinding of the other is effected by rotating the crank handle 18 in a given direction. When the handle is released the wound spring unwinds while the unwound spring winds until a balance of forces is effected, at which time the spring which was originally unwound winds, and vice versa. At this time the direction of rotation of the shaft 16 is reversed and this process continues until all of the initial energy stored in the originally wound springs is dissipated.

Secured to the end of the shaft 16 remote from the crank handle 18 is a hollow arm 31 which extends substantially at right angles to the shaft 16. The hollow arm 31 is adapted to support a rod 32 which is disposed within the hollow arm 31 and is slideable with respect thereto. Therefore, the total length of the transverse arm may be adjusted and the position of the arm 32 may be maintained by tightening a thumb screw 33. The arm 32 is provided with a weight 34 and terminates at its end in a loop 36 to which a jump rope 37 may be tied. The purpose of the weighting of the arm 34 is two-fold. In a first instance, it serves to increase the moment of inertia of the transverse arm to which the rope 37 is attached, and therefore by adjusting the total length of the arm comprising the members 31 and 32, the rate at which the rope is rotated may be controlled. The other purpose for the weight 34 is to reduce the angular velocity of the rope on upward movement of the arms 31-32 to thereby simulate the motion of a jump rope propelled by human means. It will be observed that upward movement of a jump rope, after passing through the lower dwell, is relatively slow compared with its downward movement. It is essential that the mechanism of the present invention simulate the precise conditions normally encountered and this is effected by the appropriate weighting of the arms 31, 32 with respect to the motor force provided by the springs 22 and 23.

Since the arms 31-32 is weighted and therefore will produce a considerable downward force while moving from its uppermost position to its lowermost position, the end of the frame 1 constituting the U-shape member 3 and legs 8 must be appropriately weighted to prevent the

legs 8 from being pulled off the ground by the downward thrust of the arm at the opposite end.

In a second embodiment of the present invention, illustrated in Figures 6 and 10 of the accompanying drawings, a long flexible leaf spring 38 is secured to the wheel 21 and extends radially therefrom. The spring 38 is positioned about the circumference of the wheel 21 such that it is disposed immediately under the center bar 4 when the springs 22 and 23 are at rest position. A first horizontal stop pin 39 extends from one of the legs of the U-shape member 2 toward the U-shape member 3 a sufficient distance to intercept the leaf spring 38 when it is rotated sufficiently to come into the plane of the member 39. Similarly, a horizontally extending stop member 41 extends from the other leg of the frame 2 toward the frame member 3 and is adapted to intercept the spring 38 upon its rotation into the plane of the member 41. In this embodiment of the invention, the apparatus is intended to oscillate the rope 37 through an angle less than 360°, and as illustrated in Figure 6 less than 180°. In operation the crank 18 is rotated until the spring 38 comes into contact with one of the stop members 39 and is tensioned against the stop. Upon releasing the crank handle 18 the apparatus merely rotates due to the initial tensioning of the spring 38 until the spring comes into contact with the stop 41. The inertia of the rotating system again tensions the spring 38 and therefore will effect reversal of the apparatus and produce a damped oscillation until the original force stored in the spring 38 by tensioning is dissipated.

The springs 22 and 23 are not essential to the embodiment of the invention illustrated in Figure 6 but are preferably employed, since their presence increases the period during which oscillations may be sustained. The springs 35 22 and 23 employed in this embodiment, although identical in basic structure with those employed in the first embodiment of the invention, differ in their lengths, so that they are appreciably tensioned by a rotation of the shaft 16 through only 90°, whereas those employed in the first embodiment, illustrated in Figures 1 through 5, are appreciably tensioned only upon the shaft 16 being rotated through a large number of turns. The oscillations of the mechanism illustrated in Figure 6 are sustained only if the natural frequency of the arms 31-32 is approximately equal to the natural frequency of the spring 38 and also of the springs 22 and 23, if employed.

Referring now to Figure 7 of the accompanying drawings, there is illustrated another species of the frame which may be employed to support the apparatus of the present invention. In this figure one end of the frame is provided with an inverted V-shaped member 42. The inverted V-shape member 42 includes hollow legs which are adapted to receive, internally thereof, extensible legs 43 which may be secured in a predetermined position by thumb screws 44. The legs 43 in this embodiment of the invention may terminate in flat disc-like feet 46, to increase the stability of the frame. The frame is further provided with a horizontal cross member 47 which extends perpendicular to the plane of the member 42 and is secured to the apex thereof. The member 47 is secured at its end remote from the frame 42 to a hollow vertical leg 48, which bisects the legs of the frame 42. The hollow leg 48 is adapted to receive a further leg 49 in telescoping relationship therewith and the leg 49 may be secured in a given position by a thumb screw 51. The leg 49 also terminates in a flat disc-like foot 52 to increase stability of mechanism. A first hub 53 for a crank shaft to be employed with the present invention is disposed within the hollow leg 53, while a second hub 54 is supported on radial spokes 56 between the legs of the V-shaped frame member 42.

Referring specifically to Figure 8 of the accompanying drawings, there is illustrated another form of frame member which may be employed with the apparatus of the invention. The frame illustrated in Figure 8 com-

prises two inverted V-shaped members 57 and 58 having their apices connected by a cross member 59 disposed perpendicular to the plane of the members 57 and 58. The inverted V-shaped members 57 and 58 are fabricated from hollow pipe and are adapted to receive legs 61 and 62, respectively, in telescoping relationship so that the height of the frame may be adjusted.

In all of the examples of the frame structure thus far recited it has been assumed that a telescoping leg arrangement will always be employed to adjust the height of the frame. The invention is not limited to any specific form of adjustable leg, and Figure 9 illustrates another form of adjustable leg which may be employed. The leg of the frame which is illustrated in Figure 9, and designated by the reference numeral 63, may be formed from a solid member and is provided with two hollow U-shaped members 64 and 66 displaced axially along the member 63. An adjustable rod-like leg 67 is adapted to be inserted in the hollow U-shaped members 64 and 66 and is held against the leg 63 by means of a thumb screw 68.

The apparatus of the present invention is intended to be employed by children and therefore some danger may arise from the fact that when one of the springs, as 22 and 23, is under tension as a result of the winding action provided by the crank handle 18, release of the handle will generate rapid rotation thereof, and it may strike the operator. In order to eliminate this possibility, a suitable handle structure, illustrated in Figure 2, may be employed. Specifically, the handle 18 is connected to the crank shaft 16 by means of a web member 69. The end of the web member 69 remote from the handle 18 terminates in a short stud 71 disposed perpendicular to the member 69 and directed oppositely from the handle 18. The end of the stud 71 terminates a multi-sided element 72, which is specifically illustrated as a four-sided member, for the sake of example. The end of the shaft 16 adjacent the hub 13 has a hollow four-sided aperture 73 in which the multi-sided member 72 may be seated. The handle is supported on a rod 74 which extends into an axial recess 76 in the rod 16. Disposed about the rod 74 is a spring, which biases the member 72 outwardly of the aperture 73 so that normally the member 72 does not engage the sides of the recess. As a result the handle 18 may be rotated without rotating the shaft 16. When it is desired to rotate the shaft 16 by the handle 18 the handle is pressed toward the shaft 16 so that the multi-sided member 72 is seated in the aperture 73. The shaft 16 may then be rotated and when it is wished to release the rod 16 the handle 18 is released, the spring 76 ejects the member 72 and the rod rotates without producing rotation of the handle.

While I have described and illustrated two specific embodiments of my invention, it will be clear that variations of the details of construction which are specifically illustrated and described may be resorted to without departing from the true spirit and scope of the invention as defined in the appended claims.

What I claim is:

1. A mechanism for rotating a length of flexible material comprising a relatively long shaft, spaced bearings for rotatably supporting said shaft in a generally horizontal position, a frame for supporting said bearings, a pair of spiral springs disposed about said shaft with each having one end secured to said shaft and the other end secured to said frame, said spiral springs having their convolutions directed in opposite directions from one another, an arm secured to an end of said shaft, said arm being disposed generally perpendicularly to said shaft, said arm being sufficiently heavy with respect to said springs to reduce materially the velocity of said arm upon upward movement thereof, and a handle for initially rotating said shaft so as to wind one of said springs.

2. A mechanism for rotating a length of flexible ma-

terial comprising a relatively long shaft, spaced bearings for rotatably supporting said shaft in a generally horizontal position, a frame for supporting said bearings, a source of rotary power for rotating said shaft, an arm secured to an end of said shaft, said arm being disposed generally perpendicularly to said shaft, said arm being sufficiently heavy with respect to the power capability of said source of rotary power to reduce materially the velocity of said arm upon upward movement thereof.

10 3. A mechanism for rotating a length of flexible material comprising a relatively long shaft, spaced bearings for rotatably supporting said shaft in a generally horizontal position, a frame for supporting said bearings, a pair of spiral springs disposed about said shaft with each having one end secured to said shaft and the other end secured to said frame, said spiral springs having their convolutions directed in opposite directions from one another, an arm secured to an end of said shaft, said arm being disposed generally perpendicularly to said shaft, said arm having a weight adjustably secured thereto, said weight being sufficiently heavy with respect to said springs to reduce materially the velocity of said arm upon upward movement thereof, a handle for initially rotating said shaft so as to wind one of said springs.

15 4. A mechanism for rotating a length of flexible material comprising a relatively long shaft, spaced bearings for rotatably supporting said shaft in a generally horizontal position, a frame for supporting said bearings, spring means having one end secured to said shaft and the other end engageable with said frame, a handle for rotating said shaft to displace said one end of said spring means relative to said other end thereby to tension said spring means, an arm secured to an end of said shaft, said arm being disposed generally perpendicularly to said shaft, said arm being sufficiently heavy with respect to said springs to reduce materially the velocity of said arm upon upward movement thereof.

20 5. A mechanism for rotating a length of flexible material comprising a relatively long shaft, spaced bearings for rotatably supporting said shaft in a generally horizontal position, a frame for supporting said bearings, a flat spring having one end secured to said shaft and the other end free, a pair of stop members secured to said frame and each positioned to intercept said spring adjacent its free end, said stops being disposed at predetermined spaced locations about the path of movement of the free end of said spring, an arm secured to an end of said shaft, said arm being disposed generally perpendicularly to said shaft, said arm being sufficiently heavy with respect to said springs to reduce materially the velocity of said arm upon upward movement thereof, and a handle for initially rotating said shaft so as to bring said spring into contact with one of said stops and thereby tensioning said spring.

25 6. The combination in accordance with claim 5, further comprising a pair of spiral springs disposed about said shaft, each spring having one end secured to said shaft and the other end secured to said frame, said spiral springs having their convolutions directed in opposite directions to the other.

30 7. A mechanism for rotating a length of flexible material comprising a relatively long shaft, spaced bearings for rotatably supporting said shaft in a generally horizontal position, a frame for supporting said bearings, a pair of spiral springs disposed about said shaft with each having one end secured to said shaft and the other end secured to said frame, said spiral springs having their convolutions directed in opposite directions from one another, an arm secured to an end of said shaft, said arm being disposed generally perpendicularly to said shaft, and a handle for initially rotating said shaft so as to wind one of said springs.

35 8. A mechanism for rotating a length of flexible material comprising a relatively long shaft, spaced bearings for rotatably supporting said shaft in a generally horizontal

position, a frame for supporting said bearings, a flat spring having one end secured to said shaft and the other end free, a pair of stop members secured to said frame and each positioned to intercept said spring adjacent its free end, said stops being disposed at predetermined spaced locations about the path of movement of the free end of said spring, an arm secured to an end of said shaft, said arm being disposed generally perpendicular to said shaft, and a handle for initially rotating said shaft so as to bring said spring into contact with one of said stops 10 and thereby tensioning said spring.
